UNITED STATES PATENT OFFICE.

PETER V. CORNILS, OF SAN FRANCISCO, CALIFORNIA.

LOCK.

SPECIFICATION forming part of Letters Patent No. 655,921, dated August 14, 1900.

Application filed December 4, 1899. Serial No. 739,148. (No model.)

To all whom it may concern:

Be it known that I, PETER V. CORNILS, a citizen of the United States, residing in the city and county of San Francisco, State of California, have invented an Improvement in Locks; and I hereby declare the following to be a full, clear, and exact description of the same.

My invention relates to improvements in locks for doors. Its object is to provide for a compact lock mechanism which is containable within doors having but little thickness, said mechanism comprising a series of spring-pressed tumblers and connected latch mechanism by which the bolt may be prevented from moving except by the use of the key, means by which the outside and inside knobs may be connected or disconnected at will, and means by which the bolt can be prevented 20 from moving either in its locked or unlocked position.

The invention comprises details of construction, which will be more fully explained by reference to the accompanying drawings, in 25 which—

Figure 1 is a horizontal section on line xx of Fig. 2. Fig. 2 is a vertical section on line ww of Fig. 4. Fig. 3 shows the arrangement when the lock is only used for a night-lock. 30 Fig. 4 is a vertical section on line zz of Fig. 2. Fig. 5 is a horizontal section on line yy of Fig. 2. Fig. 6 is a modification of the lock on line vv , Fig. 7. Fig. 7 is a top view of the same at right angles to Fig. 6. Fig. 8 is 35 a view of the latch. Fig. 9 is a view of the latch used in Fig. 6. Fig. 10 is a detail of the spring which presses on the latch.

The knob-shank is made in two sections A and B, one section having the inside knob 2 fixed to it and the other the outside knob 3. The abutting ends of the two shanks are constructed as follows: Upon the part A is the enlarged hollow sleeve 4, into which fits the enlarged end 5 of the shank B, so that this 45 end 5 is turnable within the cylindrical sleeve 4. A slot 6 is made across the end of the part 5, and the correspondingly-shaped plate 7 is slidable longitudinally in the shank A and is normally pressed forward by a spring 8, which forces it into engagement with the slot 6. In this condition both knobs are turnable together, and the locking mechanism may

be so disposed that the door can be opened equally from either side. When the door is to be secured so that it can only be unlocked 55 by the use of a key from the outside, the interlocking plate 7 is withdrawn by means of a button 9, which is directly connected with the stem of the plate 7, this button projecting through the end of the knob 2, as shown. 60 The inner end of the button-shank has a slot which fits over a pin 10 when the plate 7 engages the slot 6; but when the plate 7 is drawn back out of engagement with slot 6 it is held in place by turning the button until 65 the slot is out of line with the pin 10.

The outer part of the spindle B contains the operating mechanism and is made in two parts to allow this mechanism to be easily introduced or removed.

A channel 11 is made longitudinally within the shank B, and within this channel the tumblers 12 are fitted and slidable. There may be as many of these tumblers as desired, and the key 13 has points 14 projecting from it to 75 different lengths, one corresponding with each of the tumblers 12. These tumblers 12 are pressed upon by springs 15, which normally press them outwardly.

16 is a latch or block fitting and slidable in 80 a transverse slot 17, made through the two parts of the enlargement 5 of this portion of the knob-shank. This block has an opening 18 made through it in the line of the tumblers, this opening being of sufficient size to allow 85 the tumblers to slide freely through the slot. One end of this block 16 is curved, as shown, and the end of the curved portion projects so as to form a pawl 19, which when the parts are in place and the tumblers properly disposed may be projected through slots 20, which are formed through the sides of the hollow sleeve 4 of the part A, as shown, and when thus projected the pawl or edge 19, engaging with the side of one of these slots 20, 95 will turn the knob-shank, and when the outer knob is turned a lug 21, projecting from the sleeve 4, will engage the slot in the slidable latch-bolt 22. This bolt moves in an exterior easing 23, which is fitted into the edge of the 100 door, so that the outer end of the latch-bolt may engage the keeper in the door-jamb or be retracted therefrom. The normal condition of this bolt is to engage the keeper and

lock the door by reason of the pressure of the spring 24 upon the rear end of the bolt; but when the lug 21 of the sleeve 4 is turned to engage the notch or slot 25 in the bolt the 5 turning of the knob will retract the latch and allow the door to be opened. When released, the spring 24 acts to force the bolt outward and cause it to again engage the keeper. The tumblers 12 have transverse slots 26 made in 10 them at different distances from the ends, and when these slots are in line with the bridge 27 of the slideable locking-block 16 this block is forced to slide in the slot 17 by means of a spring 28, so as to project the end 19 and 15 cause it to engage with the slots 20, as before described. Under these conditions the turning of the outer knob will turn both the parts B and A of the knob-shank, and the lug 21 on the part 4, engaging the slot 25 in the latch-bolt, will withdraw said bolt against the tension of the spring 24. In order to place tumblers in position to allow this block 16 to be moved out into engagement, as above described, it is necessary to insert the key 13, 20 the points 14 of which pressing upon the outer ends of the tumblers 12 will push them in against the tension of the springs 15 until all of the channels 26 are in line with the bridge 27 of the block 16. When the key has been 25 removed, the tumblers are in condition to be pushed outwardly by the action of the springs 15 as soon as the block 16 has been pushed back from its engagement with the slot 20 and so as to bring the opening 18 in line with the tumblers. This is effected by turning the 30 outer knob, when the curved face of the block 16, pressing against the interior of the sleeve, will force the point 19 inwardly against the tension of the spring 28 until the whole of the 35 block 16 lies within the diameter of the part 5. As soon as the slot 18 has been brought 40 into line with the main diameter of the tumblers 12 the springs 15 will act to push the tumblers back through this slot 18, and this 45 will carry the channels 26 of the tumblers out of line with the bridge 27 and also out of line transversely with each other. It will 50 then be impossible to move the block 16 so as to cause the edge 19 to engage the slots 20 and any turning of the outer knob will turn 55 the outer portion B of the knob independently and without acting on the inner portion A or upon the locking-bolt 22, which is actuated by the turning of A.

55 As shown in Figs. 6 and 9, the tumblers, instead of having channels which the key causes to register with the slot 18, are made in three independent lengths slideable through holes in the latch, and when the middle sections 60 are brought by the key to register with the latch they can be moved with it transversely and out of line with the remaining section.

The two parts of the shank B are guided and held in position, when placed together, by 65 pins 29, which are fixed in one segment and enter holes in the other.

The key 13 has in one side of it a groove or

channel 30, which is slideable over a projection 31, fixed in one part of the shank B and in line with the path of the key when the latter is inserted. This insures the key being placed in the proper manner when introduced. 70

It will be manifest that any reasonable number of tumblers may be employed, depending upon the size of the channel in which they 75 are fitted and movable, and that many variations of the positions of the transverse slots 26 can be made, with corresponding differences in keys as is customary in this class of locks.

The escutcheons 32 may be made concave, as 80 shown, so that if a door is unusually thin and it is necessary to have the enlargement 4 projecting outside the thickness of the door it will be inclosed within the concavity of the escutcheon, through the center of which the 85 knob-shank passes.

In some cases it may be desirable to lock the door from one side so that it cannot be opened from the other. This is effected by the introduction of a screw 33, which is adapted 90 to fit into a hole 34 in the casing 23, in which the latch-bolt 22 slides. When the bolt is extended and engages the keeper by the action of the spring 24, if this screw is introduced it passes behind the bolt and prevents 95 its being withdrawn. If it is desired to fix the bolt in its withdrawn position, the screw is introduced so as to engage with the slot 25 of the bolt after the latter has been withdrawn, and it will then retain it in its withdrawn position, which will prevent the door from 100 latching. This condition is useful where a door swings between two rooms and is in constant use.

When the device is used as a night-latch, 105 the outside knob is omitted and the inside knob gives place to a small turning knob or button. In this construction the knob-shank is turned by the key when the latter has 110 been introduced.

Having thus described my invention, what I claim as new, and desire to secure by Letters Patent, is—

1. In a lock and in combination with a spring-pressed slideable latch-bolt, knobs fixed 115 to independent shanks the meeting ends of which fit one within the other, one of said shanks having a lug for actuating the bolt, a spring-pressed plate slideable in the other knob-shank and adapted to engage a slot in 120 the end of the first-named shank whereby the knobs are turnable together, and an operating-button on the shank of the sliding plate and located exterior to the knob thereof whereby said plate may be withdrawn from 125 its locked position with the shank of the first-named knob.

2. In a door-lock and in combination with a spring-pressed slideable latch-bolt, independent knob-shanks meeting centrally and 130 transversely of the line of travel of the latch-bolt, one of said shanks having a lug adapted to engage the latch-bolt, a block slideable transversely in the other shank so as to engage

with or be disengaged from the first-named shank, and tumblers movable within the second shank and normally engaging said block to retain it out of engagement with the first-named shank.

3. In a door-lock, a spring-pressed slideable locking-bolt, independent knob-shanks meeting transversely to the line of travel of the locking-bolt, one of said shanks having a sleeve upon its inner end within which the coincident end of the other shank is turnable, and a lug engaging the locking-bolt, slots made in said sleeve, a block slideable transversely in the interior shank so as to engage with or be disengaged from the slots of the sleeve, spring-pressed tumblers slideable through an opening in said block having transverse notches adapted to be brought in line, and a spring acting to force the block outward when such alinement has been produced whereby the outer end of the block will engage the notches of the sleeve and cause the knob-shanks to turn in unison.

4. In a door-lock, a spring-pressed slideable locking-bolt, independent knob-shanks meeting transversely to the line of travel of the bolt, one of said shanks having a sleeve upon its inner end with circumferential slots, and a lug to engage the locking-bolt, and the other having a head fitting and turnable within said sleeve, a block slideable transversely in said head having a point adapted to engage with or be disengaged from the slots of the sleeve, tumblers slideable longitudinally within said knob-shank and passing through an opening in the transversely-slideable block, notches formed in said tumblers, springs by which said notches are normally held out of alinement with the block whereby it is retained within the head in which it slides and out of engagement with the exterior sleeve, a key having bits to engage the ends of the tumblers and bring the transverse slots into alinement with the sliding block, and a spring whereby said block is projected when such alinement of the slots is made.

5. In a lock, and in combination with a spring-pressed slideable locking-bolt, independent knob-shanks meeting in line transverse to the line of travel of the locking-bolt, one of said shanks having a hollow sleeve formed upon its inner end and a lug to engage the locking-bolt, the other shank having a head fitting and turnable therein, a block slideable transversely through said head and having a point adapted to engage openings made in the sleeve of the other shank, tumblers slideable longitudinally in a second shank having transverse slots, a key insertible in the end of the shank and having bits which engage the tumblers and bring the slots into line with the transverse block, a spring whereby said block is moved out to engage the exterior sleeve when such alinement is effected and springs pressing upon the tumblers to force them back and carry the slots out

of alinement when the block has been retracted into the slide whereby the knob-shanks are disengaged.

6. In a lock and in combination with a spring-pressed slideable locking-bolt, independent knob-shanks meeting in a line transverse to the line of travel of the locking-bolt, one of said shanks having a hollow sleeve upon its inner end, with peripheral openings and a lug adapted to engage the locking-bolt a head formed upon the other shank turnable within said sleeve, a block slideable transversely through said head having one end curved or beveled and forming a catch or point to engage the slots in the sleeve when projected, a spring acting upon the opposite side to project the block, tumblers slideable longitudinally in the shank, said tumblers having transverse notches which when brought into line with the slideable block, allow it to be projected to engage with the surrounding sleeve, whereby said sleeve and the locking-bolt are moved by turning this knob-shank in one direction, and the block is retracted by contact of its beveled end with the sleeve when turned in the opposite direction, and springs by which the tumblers are moved to carry the slots out of the line of travel of the block.

7. In a lock, and in combination with a spring-pressed slideable locking-bolt, independent knob-shanks, one meeting transversely to the line of travel of the locking-bolt, one having a hollow sleeve with lug to engage the locking-bolt and the other a head fitting and turnable in said sleeve, with a transversely-slideable spring-pressed block adapted to engage the sleeve when projected, spring-pressed tumblers slideable longitudinally in said shank and through an opening in the slideable block, said tumblers being normally held in position to retain the block within the head, slots formed transversely of the tumblers, a key having bits so formed as to move the tumblers through the sliding block until the transverse slots are in line therewith, a spring by which the block is then projected to engage with the surrounding sleeve, a slot or channel formed in the key-shank and a pin within the channel in which the key fits over which said slot is slideable when the key is properly introduced.

8. In a lock, a spring-pressed slideable latch-bolt, a knob-shank standing transversely to the line of travel of the bolt having a lug adapted to engage and retract the bolt when the knob-shank is turned, a casing for the knob-shank and a screw passing therethrough and adapted to engage the locking-bolt to prevent its being retracted, or to hold it in its retracted position.

9. In a door-lock and in combination with a spring-pressed slideable latch-bolt, independent knob-shanks meeting intermediately and transversely of the line of travel of the latch-bolt, one of said shanks having a lug

adapted to engage the latch-bolt, a block slide-
able transversely in the other shank so as to
engage with or be disengaged from the first-
named shank and tumblers movable within
5 the second shank and normally locking the
block out of engagement with the bolt-actu-
ating shank, said tumblers being movable to
bring portions thereof to coincide with the

slidable block whereby it is released and mov-
able to engage with the bolt-actuating shank. 10

In witness whereof I have hereunto set my
hand.

PETER V. CORNILS.
